UNITED STATES PATENT OFFICE

2,497,714

HAIR CURLER

Harold R. Bein, Westfield, Mass.

Application February 18, 1949, Serial No. 77,241

3 Claims. (Cl. 132—42)

1

This invention relates to apparatus for waving and curling hair.

The principal objects of the invention are directed to a device for waving and curling the hair which is characterized by its simplicity of operation and efficiency in attaining the desired results.

According to the novel features of construction, the maximum control of the hair is possible in the winding operation, the end papers commonly used in winding operations are eliminated, and the hair is wound under uniform tension to produce a more perfect curl or wave formation than is possible with prior art devices.

According to certain novel features of construction the ends of the hair are not bunched, the winding of the hair is accomplished readily and easily and the desired results may be obtained by an unskilled person, whereas prior art devices require considerable skill in their operation.

The device because of its novel form is adapted to pick up the natural trends of the hair and operate so as to wind the hair naturally.

The winding member is readily insertable in and withdrawable from the device and functions with the device for the utmost control in the winding operation.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawings wherein:

Fig. 1 is a plan view showing the winding arbor of the invention with the retainer thereof associated therewith;

Fig. 2 is a plan view of the winding member of the apparatus;

Fig. 3 is a plan view of the retainer of the invention and

Fig. 4 is an end elevational view of the device of my invention as shown in Fig. 1.

Referring now to the drawings more in detail, the invention will be fully described.

A winding arbor 2 is provided which is in the form of a cylinder having concave longitudinal sides, as shown.

Intermediate the ends of the member 2 there are alternate grooves and ridges 4 and 6. The ridges in cross section are preferably formed

2

similarly to involute gear teeth. The depth of the grooves, as will be observed, decreases outwardly from the central portion of the member 2.

It has been found that the member formed substantially as shown and described may be easily and readily manipulated as by rotating for winding up the hair for waving and curling with the result that the wave or curl produced is natural in appearance, the ends of the hair are not bunched or distorted, the winding is controllable and is uniform.

The member 2 may be formed from various materials such as wood, plastics and the like.

A winding member 8 is provided which has a tapering end 10 that is insertable and frictionally engageable in sockets 12 in opposite ends of the member 2.

This member 8 may be cylindrical in form and may be made from wood, plastic or the like as may be desired.

A retainer 14 is provided which in the form of the invention shown is an elongated strip having a central opening 15 provided with inwardly extending longitudinal convexed edges 16 which are substantially complementary to the concave sides of the member 2.

Opposite ends of the member 2 are provided with concave seats 20 and the end edges of the opening 16 of member 14 are substantially convex to provide tabs 24 which are receivable in the seats 20 of the member 2.

The member 14 will be made from material which is pliable or resilient so that it may be disposed around the member 2 with the tabs 24 thereof in the seats there as in Fig. 1.

In operating, the member 8 is inserted in the socket at one end of the member 2 and by manipulating the members 8 and 2 hair may be wound on the arbor by rotating it. The amount of hair being wound and the number of turns given the arbor may vary within wide limits according to the results desired.

With the winding operation completed as desired, the retainer is slipped over the arbor with the tabs in the seats thereof whereby it is releasably held. The sides of the opening of the retainer substantially coincide with the sides of the arbor and hold the windings of hair until it is desired to remove the arbor when the retainer is removed and the hair unwound.

The retainer may be applied while the member 8 is associated with the arbor or it may be removed for that purpose, the procedure depending on the user.

The invention may be embodied in other spe-

cific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. A device for receiving windings of hair for waving or curling the same comprising in combination, an elongated cylindrical body of a certain length having alternate annular grooves and ridges intermediate opposite ends thereof and relatively smooth end surface portions outside said grooves and ridges and at opposite ends of said body, the outer peripheral faces of said ridges and end surface portions curving outwardly in opposite directions from intermediate opposite ends of said body to said opposite ends whereby said body is of relatively larger diameter at its opposite ends than intermediate said ends, a retainer of resilient stretchable material having an elongated opening therethrough which is provided with longitudinal side edges complementary to the contour of the sides of the body and opposite end edges for engaging opposite ends of the body, the length of said opening being slightly less than said certain length of the body, said retainer being manually longitudinally stretchable for receiving said body in the opening thereof whereby when released the end edges of said opening yieldingly embrace opposite ends of the body and the longitudinal side edges of said opening tend to lie against longitudinal sides of the body.

2. A device for receiving windings of hair for waving or curling the same comprising in combination, an elongated cylindrical body of a certain length having alternate annular grooves and ridges intermediate opposite ends thereof and relatively smooth end surface portions outside said grooves and ridges and at opposite ends of said body, the outer peripheral faces of said ridges and end surface portions curving outwardly in opposite directions from intermediate opposite ends of said body to said opposite ends whereby said body is of relatively larger diameter at its opposite ends than intermediate said ends, a retainer of resilient stretchable material having an elongated opening therethrough which is

provided with longitudinal side edges complementary to the contour of the sides of the body and opposite end edges for engaging opposite ends of the body, the length of said opening being slightly less than said certain length of the body, said retainer being manually longitudinally stretchable for receiving said body in the opening thereof whereby when released the end edges of said opening yieldingly embrace opposite ends of the body and the longitudinal side edges of said opening tend to lie against longitudinal sides of the body, said body having opposite transverse end faces and the end edges of the opening in the retainer having engageable recesses and projections for engagement with the end faces of said body.

3. A winding device for receiving windings of hair comprising in combination, an elongated cylindrical body having alternate annular grooves and ridges intermediate opposite ends thereof and relatively smooth end surface portions at opposite ends of said body, the outer peripheral faces of the ridges and the end surface portions of said body curving outwardly in opposite directions from intermediate opposite ends to the opposite ends of said body, a retainer of resilient stretchable material having an elongated opening therethrough with longitudinal side edges complementary to the contour of the sides and ends of said body for engaging said body, the length of the opening of said retainer being slightly less than the length of said body, said retainer being manually longitudinally stretchable for receiving said body in the opening thereof whereby when released the end edges of the opening yieldingly embrace opposite ends of said body and the longitudinal side edges of the opening tend to lie against longitudinal sides of said body.
